WIREWORKING MACHINE AND METHOD

Edward H. Schane, Lakewood, Ohio, assignor to
The Greif Bros. Cooperage Co., Cleveland, Ohio,
a corporation of Ohio

Application January 3, 1933, Serial No. 649,750

35 Claims. (Cl. 140—71)

The present invention relates to wire working machines, and more particularly to methods and machines for manufacturing wire garment hangers, consisting of a single length of wire bent and twisted into a body loop having a horizontal hanger bar and coat arm, and a hook by which the hanger may be supported from any suitable means.

Garment hangers of the type referred to are in quite general use and it is the object of the present invention to provide a novel machine for and method of manufacturing such hangers in large quantities at low cost, which will be simple and rugged in construction, cheap to manufacture, will require little floor space, and which will be automatic in operation.

Another object of the invention is the provision of a novel machine for forming garment hangers of the type referred to, in which wires of predetermined length are intermittently advanced through the machine and the various operations successively performed thereon at a plurality of positions or stations.

Another object of the invention is the provision of an automatic machine for manufacturing garment hangers of the type referred to, in which the wire is fed to the machine preferably in a continuous length from a reel, and the machine itself straightens and cuts the wire to length, positions the same with reference to a loop forming mandrel so that when the wire is bent to form the body loop one end will extend beyond the other, bends the wire about the loop forming mandrel to form the body loop, positions or bends the ends of the wire into parallel relation, twists the parallel ends to form the twisted shank of the hanger, and bends the long end of the wire to form a hook thereon.

Further objects and advantages of the invention will be apparent to those skilled in the art from the following description of the preferred embodiment thereof, described with reference to the accompanying drawings, in which:

Fig. 1 is a front elevation of a machine embodying the present invention.

Fig. 2 is a rear elevation of the machine shown in Fig. 1.

Fig. 3 is a plan of the machine shown in Figs. 1 and 2.

Fig. 4 is a section approximately on the line 4—4 of Fig. 3, with portions shown in elevation.

Fig. 5 is a section approximately on the line 5—5 of Fig. 3, with portions shown in elevation.

Fig. 6 is a section approximately on the line 6—6 of Fig. 3, with portions shown in elevation.

Fig. 7 is a section approximately on the line 7—7 of Fig. 3, with portions shown in elevation.

Fig. 8 is a section on the line 8—8 of Fig. 3.

Fig. 9 is a section on the line 9—9 of Fig. 4.

Fig. 10 is a section on the line 10—10 of Fig. 6.

Fig. 11 is a section on the line 11—11 of Fig. 10.

Fig. 12 is a section on the line 12—12 of Fig. 3.

Fig. 13 is a section on the line 13—13 of Fig. 3, and

Fig. 14 is an elevation of a finished garment hanger.

Similar reference characters designate corresponding parts throughout the several figures of the drawings.

In general the machine consists of a plurality of intermittently operated feed rolls supported at one side of a frame, adapted to draw wire from a reel through straightening rolls and feed the same across a horizontal bed and underneath one end of a loop forming mandrel supported thereabove. The wire is cut to predetermined length and positioned with reference to the loop forming mandrel so that when the same is bent around the mandrel the one end will be longer than the other. Thereafter the wire is intermittently transferred or moved in predetermined timed relation to the feeding operation in a direction normal to the feed direction, through a plurality of stations hereinafter referred to as the loop forming, shank forming, twisting, and hook forming stations, at which stations the various operations such as bending the wire about the loop forming mandrel to form the body loop, bending the ends of the wire to form the parallel shank portion, twisting the parallel ends to form the twisted shank, and bending the long end of the wire to form the hook thereon are performed by suitable dies located at the different stations. The operations are intermittently performed simultaneously upon a plurality of wires in various stages of production and the transfer of the wires from station to station takes place simultaneously during the interim between operations.

Referring to the drawings, the frame of the machine designated in general by the reference character A, consists of a base 10, a horizontal bed 11 supported by legs 12 and provided with a plurality of bosses 13 and 14, in which a drive shaft 15 is rotatably supported, 18 and 19 in which a cam shaft 20 is rotatably supported, 21, 22, and 23 in which the cam shaft 24 is rotatably supported, and 26 and 27 in which the cam shaft 28 is rotatably supported.

The drive shaft 15 is driven from an electric

motor 33 supported on the bed 10 through a flexible connection in the form of a sprocket chain 34, connected to a drive sprocket 36 on the motor shaft 38, and a driven sprocket 39 rotatably supported on the shaft 15 and adapted to be operatively connected thereto by a manually operated clutch 40. The clutch 40 may be of any well known construction and per se forms no part of the present invention and will not be described in detail. The clutch is adapted to be operated from any convenient part of the machine by mechanism which may include any desired arrangement of levers and/or shafts, etc. The clutch mechanism illustrated includes a clutch thimble 41 adapted to be reciprocated along the shaft 15 to engage and disengage the clutch by a lever 42 secured to a rod or shaft 43 slidably supported in brackets attached to the legs 12. The rod 43 is operated by a manually operated lever 44 pivotally connected to the frame of the machine. The cam shaft 20 is driven from the drive shaft 15 through spur gears 45 and 46 fixed to the drive shaft 15 and the cam shaft 20, respectively, and the cam shafts 24 and 28 are driven from the cam shaft 20 by miter gears 48, 49 and 50, 51 respectively.

The wire indicated by the reference character W is fed into the machine preferably from a reel (not shown) by intermittently driven feed rollers 55 and 56 which draw the same through sets of horizontal and vertical straightening rolls 57 and 58 respectively.

The lower feed roll 55 is keyed to one end of a short shaft 60 rotatably supported in a bearing member 61 supported in a rectangular opening 62 in a bracket 63 bolted or otherwise secured to the bed 11. The upper feed roller 56 is keyed to one end of a feed shaft 65 rotatably supported in a bearing member 66 slidably supported in the rectangular opening 62, and a bearing 67 formed on a bracket 68 secured to the bed 11. The bearing member 66 is continuously urged in an upwardly direction to disengage the rollers 55 and 56 by springs 70 positioned in the rectangular opening 62, between the bearing members 61 and 66, and is moved in a downwardly direction to engage the rollers 55 and 56 by cam members 71 and 72 projecting through slots in a cover plate 74 bolted to the bracket 63 and adapted to engage the top of the bearing member 66. The cam members 71 and 72 are keyed to a short shaft 73 rotatably supported in bosses formed on the top of the cover plate 74 and provided with a hand grasp lever 78 keyed thereto.

The lower feed roller 55 is driven from the feed shaft 65 by spur gear 80 keyed to the shaft 65 and a similar gear in mesh therewith and keyed to the shaft 60. The feed shaft 65 is driven from the cam shaft 24 by a crank disk 83 keyed to one end thereof and provided with an adjustable crank pin 84, through a connecting rod 85 and a sector plate 86 pivotally supported on a stud shaft 87 fixed to a leg 88 which supports the outer end of the bracket 68. Opposite ends of the connecting rod 85 are pivotally connected to the crank pin 84 and a pin 90 fixed to the sector plate 86 above the pivot or stud shaft 87. Gear teeth 92 formed on the outer edge of the sector plate 86 are continuously in mesh with a pinion 93 rotatably supported on the feed shaft 65 and operatively connected thereto by a one-way driving clutch, preferably a pawl and ratchet mechanism, designated in general by the reference character 95, the de-

tails of construction of which are not illustrated or described as they are well known in the art. The crank pin 84 is adjusted radially of the crank disk 83 to vary the throw of the crank and in turn the feed, by a threaded rod 96 rotatably supported in the crank disk 83 and having threaded engagement with the crank pin 84.

In the feed mechanism illustrated the amount of wire fed at each operation is adjusted by moving the crank pin 84 radially of the crank disk 10 83, the feed rolls being continuously in engagement with the wire, and the hand lever 78 being operated only when it is desired to operate the machine without the feed mechanism. It is to be understood that any feed mechanism, such as 15 continuously driven feed rolls periodically closed so as to feed the wire intermittently, may be used in place of that illustrated, the mechanism illustrated merely being the preferred construction.

As the wire is fed into the machine it passes over a removable steel plate 100 in the bed 11, which can be replaced upon wear, and under a loop forming mandrel 101. When the required amount of wire has been fed the free end thereof 25 of either engages a gauge stop 102 carried on a rod or bar 103 slidably supported in a bracket 104 on the bed 11, or lies adjacent thereto. The wire is then severed by a cutter 107 secured to a cutter arm 108, slidably supported in a bracket 30 109 bolted to the bed 11. The cutter is continuously urged in a direction to retract the same from the path of the wire by a spring 110 and is moved in an opposite direction to cut the wire by a cam disk 112 fixed to the cam shaft 28, 35 through a lever 113 pivoted at 114 to the bed 11, one end of which is operatively connected to the cutter arm 108 and the other end provided with a roller 115 for engagement with the cam disk 112.

As previously stated, the wire is positioned with reference to the loop forming mandrel 101 in such a manner that the one end thereof will project beyond the other when the same is bent about the mandrel. The hook is formed in the long end of the wire and it is desirable that this end of the wire be of constant length and that any variation in the length of wire fed be absorbed in the short end thereof. In the embodiment of the invention illustrated, the long end 45 of the wire is on the left as viewed in Fig. 3, and after the wire has been severed by the cutter 107, the gauge stop 102 is moved to the right as viewed in Fig. 3, by a cam 118 fixed to the cam shaft 24 to always return the end of the wire adjacent thereto to the same position. Preferably the wire is fed just short of the gauge stop 102 since, under some circumstances, it would not be adequate to prevent overfeed of the wire 50 depending upon the wire itself and the particular feeding mechanism employed. The rod or bar 103 carries a cam roller 119 which engages the cam 118 and the roller is always held in engagement with the cam by a spring 120, one 55 end of which is fixed to a pin on the rod or bar 103 and the other end to a pin or bracket 104.

The loop forming mandrel 101 is generally triangular in shape to conform to the shape of the body loop desired, but if other shapes of 70 body loops are desired the shape of the mandrel may be so modified to conform thereto, and is supported entirely from the front end thereof which is the left as viewed in Fig. 8, by a boss 123 formed integral therewith. The boss 123 is 75

5 bolted to the bed 11 by bolts 124 and the remaining or triangular part of the mandrel 101 is spaced from the bed as previously stated, to provide space for the passage of the wires underneath. The loop forming mandrel 101 may be made of tool steel, if desired, but, as illustrated, is made of ordinary steel with tool steel inserts 125 at the places where it is subject to wear due to the action of the forming dies, etc., and carries a stationary die 126 secured thereto by machine screws, or in any convenient manner. The stationary die forms the apex of this triangle and functions in a manner hereinafter referred to.

15 The loop forming mandrel 101 is stationary and the wires are moved therealong from station to station by a plurality of feed bars 128 and 129, the former of which are slidably supported in suitable grooves in the mandrel 101 and the 20 latter in similar grooves in the bed 11.

One end of the transfer bar 128 is adjustably connected to a triangular shaped member 131 by adjusting screws 132 which engage opposite sides of blocks 133 fixed to the member 131. 25 The adjusting screws 132 are threaded into rectangular blocks 134 carried by the transfer bars 128. The other end of the transfer bar 128 is connected to a member 136 somewhat similar to the member 131. The transfer bars 129 are 30 adjustably connected to the triangular member 131 by similar adjusting screws 137 threaded into rectangular blocks 138 carried by the transfer bars 129. The transfer bars 128 and 129 are provided with a plurality of spaced transfer 35 fingers 140 pivotally connected by pins 141 in slots 142 formed in the bars. The transfer fingers 140 are continuously urged in an outward direction to engage the wires by springs 143 positioned between the same and plates 144 secured 40 to the under side of the feed bars.

The members 131 and 136 are secured to a shaft 145, slidably supported in the boss 123 of the mandrel 101 and a bushing 146 in the other end of the mandrel, by set screws 147 and 148. 45 The shaft 145 is non-rotatably keyed in the boss 123 by a pin 149 carried thereby and which engages in a slot 150 in the shaft, and is moved towards the right, as viewed in Fig. 8, to advance the wires from station to station through the 50 machine by a cam 151 on the cam shaft 20. A cam roller 152 rotatably supported in a cap member 153 secured by a pin to the front end of the shaft 145 is continuously held in engagement with the cam 151 by a spring 154 positioned 55 over a reduced end of the shaft 145 and compressed between the shoulder formed thereon by the reduced end and the mandrel 101.

The transfer mechanism is operated in predetermined timed relation to the other operations of the machine and advances the wires from 60 station to station during the interim between the forming operations. While the wires are held in the forming dies the transfer mechanism is returned moving the transfer bars to the left as viewed in Fig. 8, and the transfer fingers retract into the bars as they pass under the wires. The lower transfer bars 129 have five transfer fingers each, the front fingers of which transfer the wire from the feeding position to 65 the first station and the last fingers eject the finished hanger from the machine. The upper transfer bars have only four transfer fingers each, those corresponding to the front fingers of the lower transfer bars 129 being omitted because the wire has not yet been bent up around 70

the loop forming mandrel when it is transferred from the feeding position to the first station.

After the wire has been transferred from the feeding position to the first station, it is in the position illustrated in full line in Fig. 4, and at this station it is bent about the loop forming mandrel 101 to the position illustrated in dotted lines, by two dies 155 and 156 pivotally connected to the under side of the bed 11 by pivots 157 and 158, respectively. The dies 155 and 156 are 10 swung up through suitable openings 159 in the bed 11 to the position shown in dotted lines by a cross-bar 160, slidably supported on a shaft 161 secured to the under side of the bed 11 by a flange member 162, and operatively connected 15 to the dies 155 and 156 by links 163 and 164, respectively. The cross-bar 160 is reciprocated in predetermined timed relation to the other operations of the machine by a lever 168 pivoted between its ends to a projection 169 on the bed 20 11 by a pivot pin 170. One end of the lever 168 is pivotally connected to the cross-bar 160 by pins 171, and the other end to a rectangular block 172 adjustably secured to the lower end of a lever 173 by nuts 174. The lever 173 is reciprocated vertically by the engagement of a cam roller 176 carried thereby in a box cam 177 fixed to the cam shaft 24, and is guided in the vertical movement by the engagement of the cam shaft 24 in a slot 178 formed in the upper end of 30 the lever. A tension spring 179, one end of which is attached to the rectangular block 172 and the other end to the base 10, is employed to balance the weight of the mechanism operated by the box cam 177 but may be omitted if desired. 35

While the dies 155 and 156 are in the closed or upper positions shown in dotted lines in Fig. 4, the wire is given a final set about the loop forming mandrel by horizontally movable dies 181 and 182. The dies 181 and 182 are carried 40 by slide members 183 and 184, slidably supported in slots formed in the front faces of members 185 and 186, bolted to the bed 11 by bolts 187 and 188, and held in position therein by cover plates 189 and 190 respectively. The 45 slide members 183 and 184 are moved towards and from the loop forming mandrel 101 to engage the dies 181 and 182 with the dies 155 and 156, while these latter dies are in their upper position by cams 193 and 194 on the cam shafts 50 24 and 28, which engage cam rollers 195 and 196 carried by the members 183 and 184 respectively. The cam rollers 195 and 196 are held in contact with the cams 193 and 194 by tension springs 199 and 200, the ends of which are attached to pins 201 and 202 secured to the top of the slide members 183 and 184 and to pins 203 and 204 secured to the top of the members 185 and 186. 55

As the wire is bent around the loop forming mandrel 101 the ends of the same are guided to a crossed position by sheet metal guides 205 and 206 secured to the top thereof. The guides 205 and 206 are not essential to the operation of the machine as the wires will be properly positioned 60 as they are bent around the mandrel by grooves 207 and 208 in the faces of the dies 155 and 156, which engage the wire and prevent the same from bending to either side.

The operation in the first station may be summarized as follows: With the parts in the position illustrated in Fig. 4 the dies are all open and a wire has just been transferred from the feeding position to the first station. Continued rotation of the cam shafts 24 and 28 causes the box cam 75

177 to move the lever 173 downwardly and through the lever 168, the cross-bar 160, and the links 163 and 164, the dies 155 and 156 about their pivots 157 and 158, whereby the ends of the wire are bent up around the loop forming mandrel 101. While the dies 155 and 156 are in this upper position, cams 193 and 194 move the dies 181 and 182, through the roller 195 and 196 and the slide members 183 and 184 to engage the dies 155 and 156 and give the wire a final set. While the dies are in their closed position and the wire is held thereby, the transfer mechanism is returned to its starting position and the transfer rods 128 and 129 retracted or moved to the front to engage the next following wire, the transfer fingers 141 receding into the rods as they pass underneath the wire held in the dies, after which the bending dies are withdrawn or moved to their open position, the dies 181 and 182 by the springs 199 and 200 and the dies 155 and 156 by the box cam 177 and/or the weight of the cross-bar 160 etc.

After the dies have released the wire the transfer mechanism is again operated to transfer the wire in the first station to the second station and the following wire from the feeding position to the first station.

The wire reaches the second station in the form illustrated in full lines in Fig. 5 and is bent into the form shown in dotted lines in this station by the stationary die 126 and cooperating movable dies 214 and 215. The movable dies 214 and 215 are carried by slide members 216 and 217 slidably supported in slots formed in the rear faces of members 185 and 186 and held in position therein by cover plates 218 and 219 respectively. The slide members 216 and 217 are moved towards the loop forming mandrel 101 to carry the movable dies 214 and 215 towards the stationary die 126 by cams 222 and 223 carried by the cam shafts 24 and 28, which engage cam rollers 224 and 225 carried by the members 216 and 217, respectively. The cam rollers 224 and 225 are held in contact with the cams 222 and 223 by tension springs 226 and 227, the ends of which are attached to pins 230 and 231 secured to sides of the members 185 and 186 and to pins 232 and 233 secured to the members 216 and 217. The faces of the dies 214 and 215 are formed with grooves 234 and 235 which engage the wire as the same is being bent and guide the ends thereof in parallel vertical relationship.

It is thought that the operation in this station will be apparent from the foregoing description, suffice it to say that the dies 214 and 215 are operated in predetermined timed relation to the other operations of the machine and that while the wire is held in the dies the transfer mechanism is retracted in preparation for advancing the wires another step or to the next succeeding station in the machine.

The wire reaches the third station in the form illustrated in Fig. 6, and at this station the projection or upstanding edges of the wire are twisted together leaving the wire in the form shown in Fig. 7. The twisting mechanism illustrated comprises a twisting gear 240 provided with a hub 241 and rotatably supported in a cylindrical or counterbored aperture 242 in a member 243. The twisting gear 240 is provided with a flared radial slot 245, the extremity of which embraces one tooth and two tooth spaces. The slot 245 extends past the center of the gear a distance approximately equal to the diameter of the wire to be twisted and the bottom of the slot is only wide

enough to accommodate the wire to be twisted. When the slot 245 extends into the hub 241 it is made larger than the corresponding part in the gear 240 to permit the wire enclosed by the hub to be twisted. If desired the hub 241 may be omitted altogether from the twisting gear or the slot therein made the same as in the gear. When the hub 241 is omitted the gear takes its bearing at the periphery of the teeth.

The twisting gear 240 is continuously in mesh with a gear 250 rotatably supported in an aperture 251 in the member 243 and keyed to the lower end of a vertical spindle 252. The spindle 252 is rotatably supported at its lower end in the member 243 by the gear 250 and at its upper end by a center in the form of a screw 253 threaded into a member 254 fixed to the top of a rod 255 secured in the member 243. The screw 253 may be adjusted to take up wear etc. and is held in any adjusted position by a lock nut 256. The gear 250 is provided with a hub 258 similar to the hub 241 on gear 240 and both gears are held in position in the apertures 242 and 251 by a cover plate 260 bolted to the member 243.

The gear 250 is provided with an enlarged tooth 261 to mesh with the slot 245, and both the member 243 and the cover plate 260 are provided with slots 263 and 264, respectively, to allow the projecting ends of the wire to engage in the slot 245 in the twisting gear 240 as the gear is moved towards the right as viewed in Fig. 6. The member 243 is bolted to a slide member 266 slidably supported on the bed 11 between the member 185 and a member 267 secured to the bed 11 by the bolts 268, and the entire twisting mechanism is moved towards and from the wire in predetermined timed relation to the other operations of the machine, by a box cam 270 carried on the cam shaft 24 and operatively connected to the slide member 266 by a cam roller 271 secured on a projecting arm 272 on the member 266.

The twisting gear 240 is rotated from the spindle 252 through the gear 250 by vertical movement of a nut 275 which has threaded engagement with a spiral slot 278 in the spindle 252. As illustrated the nut is non-rotatably carried in a vertically movable member 279 guided by the rod 255. The member 279 is reciprocated along the rod 255 by a lever 280 pivotally supported by a pin 281, in projections 282 and 283 on the slide member 266. The right hand end of lever 280, as viewed in Fig. 6, is Y-shaped and the projecting prongs 285 and 286 are pivotally connected by pins 287 and 288 to upstanding lugs 289 and 290 on the member 279. The other end of the lever 280 is provided with a cam roller 292 adapted to be engaged and operated by a cam 293 carried on the cam shaft 24. A spring 294 retains the cam roller 292 in engagement with the cam 293 and returns the lever 280 to its starting position after the ends of the wires have been twisted.

In operation it is necessary that the twisting gear 240 be stopped with the slot 245 opening towards the wire or the right, as viewed in Fig. 6 or 10, so that the twisting gear can be moved over the wires before twisting and away from or clear of the wires after twisting. The position of the slot 245 at any particular time is determined by the position of the nut 275. In the embodiment illustrated the lower positions of the nut 275 are determined by the cam 293 and the upper position by an adjusting screw 295 threaded into a plate 296 bolted to the projections 282 and 283 and locked in any adjusted position by a lock 75

nut 297. A member 298 secured to the underside of the slide member 266 and having a slot in its face adjacent the stationary die 126 is adapted to engage the left hand vertical wire, as viewed in Fig. 6, when the twisting mechanism is moved over the wire preparatory to twisting, and hold the wire clamped therebetween and the stationary die 126 during the twisting operation.

A slide member 300 slidably supported in a slot formed in the top of the member 301 bolted to the top of the bed 11 by bolts 302 carries two narrow plates 303 and 304 secured to one end thereof. The member 300 is held in position in the slot in the member 301 by a cover plate 305 secured to the top of the member 301, and is reciprocated towards and from the twisting mechanism by a cam 307 carried on the cam shaft 28, and which engages a cam roller 308 carried on the right hand end thereof as viewed in Fig. 6. The cam roller 308 is held in engagement with the cam 307 by a tension spring 310, one end of which is attached to a pin 311 secured in the cover plate 305, and the other end to a pin 312 secured in the member 300. A slot 314 in the cover plate 305 permits free movement of the pin 312 and the member 300.

The upper plate 303 is adapted to fit or slide into the slot 264 in the cover plate 260 and is provided with a slot 315 through which the wires project. The lower plate 304 is provided with a groove 316 in the face thereof adjacent the stationary die 126 adapted to engage the right hand vertical wire as viewed in Fig. 6, when the member 300 is moved to the left, and hold the wire clamped therebetween and the stationary die during the twisting operation.

The twisting operation is performed in predetermined timed relation to the other operations of the machine and may be summarized as follows: With the parts in the open position illustrated in Fig. 6, the wire or hanger has just been moved to the twisting station in the form illustrated. Continued rotation of the cam shafts 24 and 28 causes both the twisting mechanism and the member 300 to be moved towards the projecting ends of the wires. This movement continues until the twisting mechanism has been advanced to where the wires are seated in the bottom of the slot 245 as shown in Fig. 10, at which time member 300 has advanced to where the plate 303 is positioned in the slot 264 in the cover plate 260 with the ends of the wire projecting through the slot 315, and the base of the projecting wires are securely held between the stationary die 126 and the member 298 and the plate 304.

The nut 275 is then moved down over the spindle 252 by the cam 293, rotating the spindle 252, the gear 250 and the twisting gear 240 approximately two revolutions to give the ends of the wire two twists. Preferably the twisting gear 240 is rotated slightly more than two revolutions and then allowed to drop back or reverse slightly because of the spring in the wire. The slot 245 will again open towards the center of the machine and the twisting mechanism and the member 300 are returned to their retracted position away from the wires. After the twisting gear 240 has been moved clear of the twisted wires the nut is returned to its upper or starting position, and the wire or hanger transferred to the hook forming station.

One means of operating the twisting gear 240 has been illustrated but it is to be understood that the gear may be operated in any convenient manner. The nut 275 could be rotatably supported in the member 279 with a one-way driving connec-

tion between the nut and the member, such as a pawl and ratchet, with which construction the nut could be returned to its upper position before the twisting gear 240 had cleared the twisted ends of the wire without untwisting the same and it is the intention to cover any such construction. In the construction illustrated it is necessary to withdraw the twisting mechanism until the twisting gear 240 clears the twisted wires before the nut 275 can be returned to its starting position. It is also necessary to twist the wires full turns in order to permit withdrawal of the twisting gear 240 therefrom, but the wires may be given any number of twists or turns desired, the two turns illustrated merely being the preferred number of turns.

The wire or hanger reaches the fourth or hook forming station in the form illustrated in Fig. 7, and in this station a hook is formed upon the projecting or long end of the wire by cooperating cylindrical and concave dies 320 and 321. The cylindrical die 320 is carried upon one end of a slide member 322 slidably supported in a groove or slot formed in the top of the member 267 and is held in position therein by a cover plate 323. The slide member 322 is reciprocated in the slot in the member 267 by a cam 325 carried by the cam shaft 24 which engages a cam roller 326 carried thereby. The cam roller 326 is held in engagement with the cam 325 by a tension spring 328, one end of which is connected to a pin 329 secured to the cover plate 323, and the other end to a pin 330 secured to the top of the slide member 322 and projection through a slot 331 in the cover plate 323.

The cylindrical die 320 forces the projecting wire into the concave die 321, upon reciprocation of the member 322 towards the right, as viewed in Fig. 7, to partly form the hook. The concave die 321 is rotatably supported in a housing 355 secured to the top of the member 301 in any suitable manner, and is provided on the circumference thereof with gear teeth 336. After the cylindrical die 320 has forced the wire into the concave die 321 to partly form the hook, the concave die is rotated about the center of the cylindrical die as an axis, to complete the hook. This rotation of the concave die is effected through a gear 338, keyed to a shaft 339, rotatably supported in the housing 355, and continuously in mesh with the gear teeth 336 on the periphery of the die 321. The shaft 339 is periodically oscillated in predetermined timed relation to the other operation of the machine, by a lever 340 keyed thereto, the free end of which is pivotally connected to one end of a rod 341, the other end of which is adjustably connected to a member 342 pivotally connected to the upper end of a lever 344. The lever 344 is pivotally supported, as at 345, to a projecting lug 346 on the member 301 and carries on its lower end a cam roller 348 adapted to be engaged and operated by a cam 349, carried by the cam shaft 28. A tension spring 350, one end of which is connected to a bracket 351 bolted to the top of the member 301, and the other end to the lever 344 above its pivot, retains the cam roller 348 in engagement with the cam 349 and returns the concave die 321 to its starting position after the hook has been formed.

A guide member 354, preferably of sheet metal, secured to the top of the member 267 and engaging the face of the housing 355, assists in guiding the end of the wire about the cylindrical die 320, but is not necessary to the operation of the ma-

chine, as the wire may be guided by other means or need not be guided at all.

The concave die 321, which as illustrated, is one-half of a gear, is rotatably supported in the housing 335 by the engagement of flanges 355 on the sides thereof in curved or arc-shaped slots on the inside walls of the housing, but it is to be understood that the die may be supported in any suitable manner, and may be directly operated from the rod 341 without the intermediate mechanism including the gear 338, etc. It is believed that the operation of the mechanism at this station will be apparent from the foregoing description thereof, suffice it to say that the completed hanger is ejected from the machine by the transfer mechanism as soon as the cylindrical die releases the same and before the cylindrical die has moved to the left far enough to open the hook. It will be noted that after the twisting 20 operation the short end of the wire lies to the right of the long projecting end of the wire, and that after the hook has been formed it lies underneath the rear of the hook in an unexposed position.

25 A completed garment hanger, indicated in general by the reference character H, is illustrated in Fig. 14, the various parts of which are indicated as follows: cross-bar 360, coat arms 361 and 362, and hook 363.

30 The wire W is preferably fed from a reel supported on a stud adjacent the machine, and adapted to be intermittently rotated through a friction or one-way driving connection at the beginning of each feeding operation to relieve the 35 pull of the reel. This feature is of particular advantage where the reel is very heavy and may be operated from the sector 86 if desired. The feeding and cutting mechanism illustrated may be omitted altogether from the machine and the 40 wire fed thereto in predetermined lengths, either by manual means or some feed mechanism adapted to automatically feed predetermined lengths of wire.

45 From the foregoing description it will be apparent that a novel machine for forming garment hangers of the type referred to has been provided, which will be simple and rugged in construction, and which will automatically produce garment hangers from a single length of 50 wire by a plurality of operations, performed on the wire as it is intermittently advanced through the machine. While all the cams with the exception of cams 177 and 270 are shown as face cams, it is to be understood that box cams could 55 be substituted therefor without changing the operation of the device, in which event the various springs used in cooperation with the face cams could be omitted and such a construction is contemplated.

60 The invention has been illustrated and described with reference to the preferred embodiment thereof, but I do not wish to be limited to the particular construction illustrated, and described, which may be varied within the scope of 65 this invention, and I particularly point out and claim as my invention the following:

1. The method of forming a coat hanger, which includes moving a predetermined length of wire in a direction normal to its axis along a mandrel, bending the wire about the mandrel, twisting the 70 ends of the wire, and forming a hook on one end of the wire during its movement along said mandrel.

2. The method of forming a coat hanger, which 75 includes feeding a continuous length of wire in

a direction parallel with its axis, cutting the wire into predetermined lengths, moving the cut lengths of wire bodily in a direction transversely of the axis longitudinal thereof through a plurality of die stations, and forming the cut length 5 of wire into a garment hanger during the last mentioned movement.

3. A wire working machine comprising a frame, means supported by said frame adapted to support a wire, means supported by said frame 10 adapted to bend the wire to form a loop, means supported by said frame adapted to twist the ends of the wire together, means supported by said frame adapted to form a hook on one end of the wire, and means supported by said frame 15 adapted to transfer the wire from one of said means to another.

4. A wire working machine comprising a frame, means on said frame adapted to support a wire, means supported by said frame adapted to bend 20 the wire to form a loop portion, means supported by said frame adapted to bend the ends of the wire into parallel relationship, means supported by said frame adapted to twist the ends of the wire together, means supported by said frame 25 adapted to bend one end of the wire to form a hook thereon, and means supported by said frame adapted to transfer the wire from one of said means to another.

5. A wire working machine comprising a frame, 30 means supported by said frame adapted to feed a continuous length of wire to the machine, means supported by said frame adapted to cut the wire into predetermined lengths, means supported by said frame adapted to bend the wire 35 to form a loop portion, means supported by said machine adapted to twist the ends of the wire together, means supported by said frame adapted to bend one end of the wire to form a hook thereon, and means supported by said frame 40 adapted to transfer the wire from one of said means to another.

6. A wire working machine comprising a mandrel, means adapted to position wire adjacent 45 said mandrel, means adapted to move said wire longitudinally of said mandrel, means located adjacent said mandrel adapted to bend the wire thereabout, and means located adjacent said mandrel adapted to twist the ends of the wire 50 together and form a hook on one end of the wire during the travel of the wire along said mandrel.

7. A wire working machine comprising a mandrel, means adapted to position wire adjacent 55 said mandrel, means adapted to move the wire longitudinally of said mandrel, means located adjacent said mandrel adapted to bend the wire thereabout, means located adjacent said mandrel adapted to twist the ends of the wire together, and means located adjacent said mandrel adapted to bend one end of the wire to form a hook 60 thereon.

8. A wire working machine comprising a mandrel, means adapted to position a wire underneath 65 said mandrel with one end thereof longer than the other, means adapted to move the wire longitudinally of said mandrel, means located adjacent said mandrel adapted to bend the wire about said mandrel, means located adjacent said mandrel adapted to twist the ends of the wire together, and means located adjacent said mandrel adapted to bend the long end of the wire 70 to form a hook thereon.

9. A wire working machine comprising a mandrel, means adapted to feed wire to said machine 75 and underneath said mandrel, means adapted to

move the wire along said mandrel, means adapted to bend the wire about said mandrel to form the body loop of a hanger, means adapted to twist the ends of the wire to form the twisted shank of the hanger, and means adapted to form a hook on one end of the wire.

10. A wire working machine comprising a mandrel, means adapted to feed wire to said machine and underneath said mandrel, means adapted to move the wire along said mandrel, means located adjacent said mandrel adapted to bend the wire thereabout to form the body loop of a hanger, means located adjacent said mandrel adapted to twist the ends of the wire to form the twisted shank of the hanger, and means located adjacent said mandrel adapted to form a hook on one end of said wire.

11. A wire working machine comprising a mandrel, means adapted to feed wire to said machine and underneath said mandrel with one end thereof longer than the other, means adapted to move the wire longitudinally of said mandrel, means adapted to bend the wire about said mandrel, means adapted to twist the ends of the wire together, and means adapted to form a hook on the long end of the wire, all of said means operating upon said wire during its travel along said mandrel.

12. A wire working machine comprising a mandrel, means adapted to feed wire to said machine and underneath said mandrel with one end thereof longer than the other, means adapted to move the wire longitudinally of said mandrel, means located adjacent said mandrel adapted to bend the wire thereabout, means located adjacent said mandrel adapted to twist the ends of the wire together, and means located adjacent said mandrel adapted to bend the long end of the wire to form a hook, all of said means operating upon said wire during its travel along said mandrel.

13. A wire working machine comprising a mandrel, means adapted to position a wire adjacent said mandrel, means adapted to intermittently move the wire longitudinally of said mandrel, means located adjacent said mandrel adapted to bend the wire around the same, means located adjacent said mandrel adapted to twist the ends of the wire together, and means located adjacent said mandrel adapted to bend one end of the wire to form a hook thereon.

14. A wire working machine comprising a mandrel, means adapted to position wire underneath said mandrel with one end projecting therefrom farther than the other, means adapted to intermittently move the wire along said mandrel, means located adjacent said mandrel adapted to bend the wire thereabout, means located adjacent said mandrel adapted to twist the ends of the wire together, and means located adjacent the mandrel adapted to bend the long end of the wire to form a hook thereon, said wire being moved from one of said means to the other in its movement along said mandrel.

15. A wire working machine comprising a mandrel, means adapted to feed wire into said machine and underneath said mandrel, means adapted to intermittently move the wire longitudinally of said mandrel, means adjacent said mandrel adapted to bend the wire thereabout, means adjacent said mandrel adapted to twist the ends of the wire together, and means adapted to bend one end of the wire to form a hook thereon, said means operating upon the wire during its travel along said mandrel.

16. A wire working machine comprising a mandrel, means adapted to position wire adjacent said mandrel, means adapted to intermittently move the wire longitudinally of said mandrel through a plurality of stations, means at 5 said stations for bending the wire about said mandrel, twisting the ends of the wire together, and bending one end of the wire to form a hook thereon.

17. A wire working machine comprising a 10 mandrel, means adapted to position a wire adjacent said mandrel, means adapted to intermittently move the wire longitudinally of said mandrel through a plurality of stations, means located at said stations adapted to bend the wire 15 about said mandrel, form the ends into parallel relationship, twist the ends of the wire together, and bend one end of the wire to form a hook thereon.

18. A wire working machine comprising a 20 mandrel, means adapted to position wire adjacent said mandrel, means adapted to intermittently move the wire longitudinally of said mandrel through a plurality of stations, means at the first of said stations adapted to bend the wire 25 about said mandrel, means at the second of said stations adapted to form the ends of the wire into parallel relationship, means located at the third of said stations adapted to twist the ends of the wire together, and means located at the 30 fourth of said stations adapted to bend one end of the wire to form a hook thereon.

19. A wire working machine comprising a mandrel, means adapted to feed a wire into said machine and underneath said mandrel with one 35 end thereof longer than the other, means adjacent said mandrel adapted to bend the wire thereabout, means adjacent said mandrel adapted to twist the ends of the wire together, means adjacent said mandrel adapted to bend one end of 40 the wire to form a hook therein, and means for transferring the wire from one of said means to the next.

20. The method of forming a garment hanger comprising a body portion and a hook, which 45 comprises bodily moving a wire through a plurality of wire forming stations, bending the wire at one of the stations to form the body portion of the garment hanger, and bending the wire at a subsequent station to form the hook of the 50 garment hanger.

21. The method of forming a garment hanger comprising a body portion, a shank, and a hook, which comprises bodily moving a wire through a plurality of wire forming stations, bending the 55 wire at one of the stations to form the body portion of the garment hanger, twisting the ends of the wire together at another of the stations to form the shank, and bending one end of the wire at a subsequent station to form the hook. 60

22. The method of forming a garment hanger comprising a body portion and a hook, which comprises moving a wire along a mandrel and through a plurality of wire forming stations, bending the wire about said mandrel at one 65 of the stations to form the body portion of the garment hanger, and bending one end of the wire at a subsequent station to form the hook of the garment hanger.

23. The method of forming a garment hanger 70 which comprises intermittently moving a wire bodily along a mandrel through a plurality of wire forming stations, bending the wire at one of the stations about the mandrel to form the body portion of the garment hanger, bending the 75

- ends of the wires to a parallel relationship at another of said stations, twisting the parallel ends of the wire at another station, and bending one end of the wire at a subsequent station to form the hook of the garment hanger.
24. The method of forming a garment hanger which comprises, feeding a continuous length of wire in a direction parallel with its axis, cutting the wire into predetermined lengths, moving the cut lengths of wire bodily through a plurality of wire forming stations, and forming the wire at said stations into a garment hanger.
25. The method of forming a garment hanger which comprises, feeding a continuous length of wire in a direction parallel with its axis, cutting the wire into predetermined lengths, moving the cut lengths of wire bodily through a plurality of wire forming stations to form the body portion of the garment hanger, and bending the wire at another of the stations to form a hook.
26. A wire working machine provided with a plurality of wire forming stations comprising, means for moving a wire bodily through a plurality of the wire forming stations, means located at one of the stations for forming a loop of the wire, and means located at a subsequent station for forming a hook on the wire.
27. A wire working machine provided with a plurality of wire forming stations adapted to form a length of wire into a garment hanger comprising, means for moving a wire bodily through a plurality of the wire forming stations, means located at one of the stations for bending the wire to form the body portion of the garment hanger, and means located at a subsequent station for bending one end of the wire to form a hook thereon.
28. A wire working machine provided with a plurality of wire forming stations adapted to form a length of wire into a garment hanger comprising, means for moving a wire bodily through a plurality of the wire forming stations, means located at one of the stations for bending the wire to form the body portion of the garment hanger, means located at a subsequent station for bending one end of the wire to form a hook thereon, and means located at one of the stations for connecting the ends of the wire at the shank of the hanger.
29. A machine for making garment hangers provided with a plurality of wire forming stations comprising, a frame member along which a wire is adapted to be moved, means for moving a wire along said frame member from one of the stations to another, means at one of the stations for bending the wire to form the body portion of the hanger, and means at a subsequent station for bending one end of the wire to form a hook thereon.
30. A machine for making garment hangers provided with a plurality of wire forming stations comprising, a frame member along which a wire is adapted to be moved, means for moving the wire along said frame member from one of said stations to another, means at one of the stations for bending the wire to form the body portion of the hanger, means at a subsequent station for bending one end of the wire to form a hook thereon, and means at another station for connecting the wires together at the shank of the hanger.
31. In a machine provided with a plurality of wire forming stations for making garment hangers from a length of wire, the combination of, a mandrel, means for moving the wire along said mandrel from one of the stations to another, means located adjacent said mandrel at one of the stations for bending the wire about the mandrel to form the body portion of the garment hanger, means located adjacent the mandrel at another of said stations for connecting the ends of the wire together, and means located adjacent said mandrel at a subsequent station for bending one end of the wire to form a hook thereon.
32. In a wire working machine provided with a plurality of wire forming stations for making a garment hanger out of a length of wire, the combination of, a mandrel, means adapted to position the wire adjacent said mandrel with one end of the wire longer than the other, means adapted to move the wire longitudinally of said mandrel, means at one of said stations for bending the wire about said mandrel to form the body portion of the garment hanger, means located at another of the stations for connecting the ends of the wire together, and means located at a subsequent station for bending the long end of the wire to form a hook thereon.
33. In a machine for making garment hangers the combination of, a mandrel, means adapted to position a wire adjacent said mandrel with one end thereof longer than the other, means for moving a wire along said mandrel through a plurality of wire forming stations, means at one of said stations for bending the wire about said mandrel to form the body loop of the garment hanger, and means at a subsequent station for bending the long end of the wire to form a hook thereon.
34. In a garment hanger forming machine the combination of, a mandrel, means adapted to position a wire adjacent said mandrel with one end thereof longer than the other, means adapted to intermittently move the wire along said mandrel through a plurality of wire forming stations, means at one of the stations for bending the wire about said mandrel to form the body loop of the garment hanger, means at one of said stations for connecting the ends of the wire together, and means at one of said stations for bending the long end of the wire to form a hook thereon.
35. In a garment hanger forming machine the combination of, a mandrel, means for positioning a wire adjacent said mandrel with one end thereof longer than the other, means for transferring the wire longitudinally of said mandrel to a plurality of wire forming stations, means located at one of the stations for bending the wire about said mandrel, a slotted gear positioned at one of said stations for twisting the ends of the wire together, and means located at one of said stations for bending the long end of the wire to form a hook thereon.

EDWARD H. SCHANE.
